(57) CLAIM

The ornamental design for an address card case, as shown and described.

DESCRIPTION

FIG. 1 is a front perspective view of the address card case showing the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof showing its lid open.

The address cards depicted by means of broken lines in FIG. 8 have been shown for illustrative purposes only and form no part of the claimed design.
